DESIGN FOR A VISE SLEEVE

Herman P. Fest, Los Angeles, Calif.

Application November 19, 1940, Serial No. 96,677

Term of patent 14 years

To all whom it may concern:

Be it known that I, Herman P. Fest, a citizen of the United States, residing at Los Angeles, in the county of Los Angeles and State of California, have invented a new, original, and ornamental Design for a Vise Sleeve, of which the following is a specification, reference being had to the accompanying drawing, forming part thereof.

Fig. 1 is a perspective view of a vise sleeve, showing my new design looking at one side thereof.

Fig. 2 is a perspective view looking at the side of the article opposite to that shown in Fig. 1.

Fig. 3 is a section on line 3—3 of Fig. 2.

I claim:

The ornamental design for a vise sleeve, substantially as shown.

HERMAN P. FEST.
